TONE-ARM FOR TALKING-MACHINES.

1,108,302.

Specification of Letters Patent.

Patented Aug. 25, 1914.

Application filed August 30, 1913. Serial No. 787,461.

To all whom it may concern:

Be it known that I, CLINTON E. Woods, of Bridgeport, Connecticut, have invented a new and useful Improvement in Tone-5 Arms for Talking-Machines, which invention is fully set forth in the following specification.

The present invention relates to tone-arms for talking machines, the object of the invention being to provide a device of the character described which will permit the sound-box to have an universal movement, which will be as nearly as possible perfect acoustically and mechanically, and in which 10 the possibility of sympathetic vibration will be reduced to a minimum. Briefly stated, these objects are attained by providing in the tone-arm a continuous, constantly expanding uninterrupted passage, to the end 15 that the sound waves are delivered with an increased volume; and in reducing to a minimum the number of parts and uniting the several members of the tone-arm by smooth, tight, practically frictionless joints 20 which obviate the possibility of rattling and the introduction of any extraneous sound.

The improved tone-arm is provided with a horizontal section and a vertical section, and the horizontal section is preferably 25 secured to the vertical section by a bayonet-joint connection which is entirely concealed and thoroughly effective and durable.

The present invention is such that, while the volume of sound is increased, the size 30 of the tone-arm is largely decreased over those heretofore employed.

The invention will be better understood by reference to the accompanying drawings, illustrating one mechanical expression of 35 the inventive idea, and in which:—

Figure 1 is a perspective view of the tone-arm; Fig. 2 is a vertical section, partly in elevation; Fig. 3 is a detail, showing various coacting parts separated; and Fig. 4 is a 40 section on line 4—4 of Fig. 2.

Referring to the drawing, wherein like reference numerals indicate like parts in the several views, 5 indicates a hollow support on which the tone-arm is mounted. Said 45 tone arm is made up of a plurality of sections, preferably a vertical section 6 provided with a horizontally extending elbow 6', and a horizontal section 7 provided with a horizontally extending elbow 7'. On the

free end of the horizontal section is secured 55 a casing 8, to which the sound-box is connected in any usual or suitable manner. The section 7 has an uninterrupted passage that continuously expands from the casing 8 to the point where said section is jointed 60 to the section 6, this passage continuing through said section 6 without interruption, to the end that the sound waves are delivered without variation or distortion. Preferably, the section 7 is a one-piece, 65 seamless, drawn tubing, as is also the section 6.

In order that the joint between sections 6 and 7 may be tight and smooth and practically frictionless, to the end that extraneous noises may be excluded and wear practically eliminated, the end of section 7 is reduced at 9, forming a continuous shoulder 10 that bears against the end 11 of the section 6. The two sections are preferably 70 secured together by a bayonet joint, constituted by ribs 12 and 13 on section 7 and ribs 14 and 15 on section 6. To the end of reduced portion 9 is secured, by screws 16 and 17, a flat annular spring 18 that presses 80 against a ridge 19 in section 6 when the parts are assembled, thus maintaining the joint tight and preventing any rattling. A stop is provided for limiting the movement 85 of the tone-arm in a vertical plane, which stop, as here shown, is in the form of a pin 20 extending through an opening 22 in the section 6 until its inner end enters a shouldered slot 21 formed in the reduced portion 9 of the tone-arm 7. 90

In order that the horizontal movements of sections 6 and 7 may be readily and noiselessly effected, the annular lower end of section 6 rests upon the annular upper end of the hollow support 5. 95

Secured in any desired manner to the inside of section 6, in order to rotate therewith, is a sleeve 23 of suitable material, said sleeve projecting down into the support 5 and being provided with a slot 24 in which engages 100 a pin 25 carried by the support 5, whereby the horizontal arc of movement of the tone-arm is limited. The sleeve 23 is provided at its lower end with two diametrically disposed notches 26, into which project tongues 105 27 similarly arranged on a ring 28 provided with parallel slits 29 and ridge 30. The lower end of said ring 28 is adapted to be

snapped into an annulus 31 provided with a lug 32. This annulus has bearing in a recess 33 in the hollow support 5, being introduced therein through a slot 34 in said support and rotating on said bearing when the tone-arm moves horizontally. The extent of movement of said annulus is limited by said slot. The lug 32 may be connected to any desired mechanism which it is desired to operate by the movement of the tone-arm as, for example, the start-and-stop mechanism.

It will be understood that the lower face of flange 35, here shown as integrally formed on the horizontal support 5, rests upon the motor board or the machine casing.

The various parts described are assembled by first introducing the annulus 31 through the slot 34 onto its bearing 33, and then snapping the lower end of ring 28 through the opening in said annulus until the ridge 30 bears upon the former. Sleeve 23 which is fixedly secured to section 6 is then introduced into the hollow support 5 until lugs 25 27 engage the recesses 26 and the lower face of section 6 rests upon the upper face of support 5. Screw 25 is then put in place with its point engaging in the slot 24 of sleeve 23. It now only remains to place section 7 in position, and this is readily effected by turning said section into a vertical position and introducing it into the open end of section 6 until spring 18 presses against the ridge 19. The spring is thus placed under tension and 35 the section is turned down to the position indicated in Fig. 1, with its lugs or ribs 12 and 13 engaging the rear faces of lugs or ribs 14 and 15. The screw 20 is then placed in position to limit the vertical movement of section 7, and the parts are now in position for operation.

The tone-arm as thus produced is smaller in size than those heretofore employed, is very simple in construction and effective in

operation, is highly attractive in appearance, 45 and is acoustically and mechanically correct, and the parts are readily constructed, assembled and disassembled.

While, for the purpose of clearness, there is herein illustrated and described in detail 50 one expression of the inventive idea, it is to be understood that the invention is not limited to the construction shown, but that the inventive idea is susceptible of many mechanical expressions within the limits of the 55 claims appended hereto.

What is claimed is:—

1. In combination, a tone-arm having a vertical section and a horizontal section, a hollow support on which the vertical section 60 rests, a sleeve secured to said vertical section and projecting into said support, a split ring connected to said sleeve to participate in its rotary movements, and an annulus member secured to said split ring. 65

2. In combination, a tone-arm having a vertical section and a horizontal section, a hollow support on which the vertical section rests, a part moving with said vertical section and projecting into said support, means 70 connected to the lower end of said projecting part to participate in its rotary movements, and a member secured to said means.

3. In combination, a tone-arm having a vertical section and a horizontal section, a hollow support on which the vertical section rests, a sleeve secured to said vertical section and projecting into said support, means 75 connected to the lower end of said sleeve to participate in its rotary movements, and a member secured to said means. 80

In testimony whereof I have signed this specification in the presence of two subscribing witnesses.

CLINTON E. WOODS.
